UNITED STATES PATENT OFFICE.

CHARLES H. NORTON, OF WORCESTER, MASSACHUSETTS, ASSIGNOR TO NORTON GRINDING COMPANY, OF WORCESTER, MASSACHUSETTS, A CORPORATION OF MASSACHUSETTS.

WHEEL-FEED FOR GRINDING-MACHINES.

1,141,205.

Specification of Letters Patent.

Patented June 1, 1915.

Original application filed June 6, 1913, Serial No. 772,055. Divided and this application filed July 22, 1914. Serial No. 852,386.

To all whom it may concern:

Be it known that I, CHARLES H. NORTON, a citizen of the United States, residing at Worcester, in the county of Worcester and 5 State of Massachusetts, have invented a new and useful Wheel-Feed for Grinding-Machines, of which the following is a specification.

This invention relates to a wheel slide for 10 a machine for grinding surfaces of rotation, especially cylindrical surfaces, and this is a division of my application on a cylindrical grinding machine, filed June 6, 1913, Serial No. 772,055.

15 The principal objects of the invention are to provide a machine of this character of a simple construction in comparison with the kind of work that it accomplishes and capable of being fully controlled and manipulated by an operator in a comparatively simple way; to provide improved means whereby the automatic reverse automatically feeds the wheel forward a step at each end of the reverse, and means whereby this 25 feed also can be operated by hand either at normal speed or very slowly.

The invention also involves improvements in combinations of parts and details of construction of the wheel feed as will appear 30 hereinafter.

Reference is to be had to the accompanying drawings, in which—

Figure 1 is a sectional view of a wheel feeding mechanism constructed in accordance with this invention; Fig. 2 is a front view of a portion of the machine with parts of the wheel feed thereon; Fig. 3 is a detail of the pawl mechanism; and Fig. 4 is a sectional view on the line 4—4 of Fig. 2.

40 The machine is shown as comprising a main casting or base A on which operates a sliding table B mounted in longitudinal ways on the top of the base. The wheel slide C operates in transverse ways toward 45 and from the sliding table which is designed to support the work.

The sliding table B is provided with the usual dogs B' which are designed to engage a reversing lever 40 and operate it. The 50 operation of this lever will not be described herein, as it is a feature of the case from which this is divided.

The reversing lever is provided with a

roller 51 which is designed to engage a projection on a feed lever 52 at the bottom. 55 This lever operates a bell crank 53 pivoted to swing on a shaft 54. The connection between the lever 52 and the crank 53 is through a screw 55 having adjusting nuts 56. The screw 55 is guided at its lower end 60 in an externally threaded socket 57. The feed lever 52 is held up by a spring-pressed buffer 58 which yields to allow the reversing lever 40 to move over the projection thereon which is located in the path of the roller 65 51. The bell crank 53 is provided with two pawls 60 designed to work in a series of teeth 61 on the edge of a ratchet wheel 62. These pawls are so spaced that first one engages a tooth and then the other engages 70 another tooth. Thus the teeth do not have to be spaced as finely as they would with a single pawl. These teeth extend throughout a part only of the circumference of this ratchet wheel. This wheel is fixed to a gear 75 63 loosely mounted to rotate on a bushing 64, which bushing is keyed to the shaft 54. Keyed to the shaft 54 is a gear 65 having a long hub, the gear 65 having one more tooth than the gear 63. Adapted to engage both 80 of these gears is a sliding pinion 66 operated by a handle 67. This handle can be pulled out so that the pinion 66 will mesh only with the gear 65 or it can be pushed into the position shown in Fig. 4, in which it 85 meshes with both gears. A spring-pressed pin 68 on a hand-wheel 69 serves to hold the handle 67 in either of its extreme positions, the handle and pinion being supported by the hand wheel.

90 The ratchet wheel 62 is provided with a spring-pressed lock 70. The hand wheel is provided with an index plate 71 having notches 72 for receiving the lock 70 so that these parts may be locked together in any 95 desired relative position. A stop 73 is pivoted at the side thereof to engage the lock 70 when thrown back and thus hold the ratchet wheel 62 from rotation.

The shaft 54 constitutes a wheel feed 100 screw, and for that purpose is provided with screw threads on the end which engage in a nut 75 fixed to hub 76 secured in a projection on the bottom of the wheel slide C. A weight 77 supported by a chain 78 fixed 105 to the bottom of this hub and passing over

an idler serves normally to hold the wheel slide back. The interior of the hub 76 is oiled through a passage 79 having a cover 80. A door 81 is provided on the base A for access to these parts.

When the handle 67 is pulled out, the hand wheel can be rotated idly, but the slide cannot be operated either by hand or power. When it is desired to feed the wheel slide 10 either by hand or power, the handle 67 must be pushed in so that the pinion 66 will mesh with both gears 63 and 65.

To feed the slide directly by hand toward the work which is carried by the sliding 15 table B, the ratchet wheel 62 and the index plate 71 are locked together by means of the lock 70, and the pawls 60 are moved upward to inoperative position. The hand wheel 69, index plate 71, ratchet wheel 62 20 and gear 63 may then be rotated as a single element. The pinion 66 also moves with them about the axis of the shaft 54 but without turning on its own axis. In this manner the gear 65 is forced to rotate with the 25 hand wheel 69 and, as the gear 65 is keyed to the shaft 54, the effect of these connections is to cause the shaft 54 to rotate in unison with the hand wheel 69.

When it is desired to feed the wheel slide 30 forward very slowly by hand, the plate 71 is released by throwing back the lock 70 and the plate 62 is locked in stationary position by the stop 73 engaging the lock 70. The rotation of the hand wheel 69 then 35 causes the screw 54 to rotate, but the rate of rotation is very greatly reduced by the differential gears 63 and 65, the difference in the number of teeth in these gears causing a very slow rotation of the gear 65 when 40 the gear 63 is held stationary.

When the screw 54 is to be rotated by power, the ratchet wheel 62 and the plate 71 are locked together and set so that the pawls 60 engage the ratchet teeth 61 near 45 the left hand end of the series of teeth. The reversing lever 40 acting through the lever 51 causes the oscillation of the feed lever 53 at each end of the traverse of the table, thus positively moving the pawls 60 50 to feed the ratchet plate 62 forward a certain definite amount. In this way the feed screw 54 will be turned to advance the wheel slide a measured distance at each reversal of the travel of the table, through the connections previously described in connection 55 with the feed of the table directly by hand.

For the purpose of rotating the grinding wheel the belt 119 passing over an idler and tightener 120, operates a shaft 121. On this 60 shaft is a pulley 122 which by belt 123, kept tight by a tightener 124, operates the grinding wheel shaft 126 on which the grinding wheel E is located. The belt tightener 120 is kept in position for performing its function by a weight 125.

On account of this construction, it will be seen that a single operator in front of the machine has full control of the machine for the purpose of causing the grinding wheel to be fed up automatically at each 70 operation of the table, or for the purpose of performing these functions by hand.

Although I have illustrated and described only a single embodiment of the invention, I am aware of the fact that modifications 75 can be made therein by any person skilled in the art without departing from the scope of the invention as expressed in the claims. Therefore I do not wish to be limited in these respects, but

What I do claim is:—

1. In a grinding machine, the combination of a feed screw, a grinding wheel slide connected therewith and operated thereby, a hand wheel and a ratchet wheel both independently and rotatably mounted with respect to the feed screw, slow speed gearing comprising a gear fixed to the ratchet wheel for connecting the hand wheel with the feed screw, means for positively connecting the ratchet wheel and hand wheel, whereby the feed screw can be operated directly by the hand wheel, and means whereby said gear can be disconnected from the hand wheel.

2. In a grinding machine, the combination of a feed screw, a grinding wheel slide connected therewith and operated thereby, a hand wheel, a ratchet wheel, slow speed gearing comprising a member secured to the ratchet wheel for connecting the hand wheel with the feed screw, means for operating the ratchet wheel by power, and means for locking the ratchet wheel in stationary position, whereby the hand rotation of the hand wheel will be transmitted to the feed 105 screw through the slow gearing.

3. In a grinding machine, the combination of a feed screw, a grinding wheel slide connected therewith and operated thereby, a hand wheel, a ratchet wheel, slow speed 110 gearing for connecting the hand wheel with the feed screw, means for operating the ratchet wheel by power, means for locking the hand wheel and ratchet wheel together, and means for locking the ratchet wheel in 115 stationary position when the ratchet and hand wheels are not locked together, whereby the hand rotation of the hand wheel will be transmitted to the feed screw through the slow gearing.

4. In a grinding machine, the combination of a feed screw, a grinding wheel slide connected therewith and operated thereby, a hand wheel and a ratchet wheel both independently and rotatably mounted with respect to the feed screw, slow speed gearing 125 for connecting the hand wheel with the feed screw, means for operating the ratchet wheel by power, means for positively connecting the ratchet wheel and hand wheel, whereby 130

the feed screw can be operated directly by the hand wheel, means for locking the ratchet wheel in stationary position when the ratchet and hand wheels are not locked together, whereby the hand rotation of the hand wheel will be transmitted to the feed screw through the slow gearing, and means whereby said slow gearing can be disconnected from the hand wheel.

10. 5. In a grinding machine, the combination with a wheel slide, of a feed screw for operating it, a hand wheel on the feed screw adapted to be positively connected thereto and disconnected therefrom, a ratchet device connected with said feed screw comprising a pawl, a ratchet wheel having teeth thereon in position to be engaged and operated by said pawl, means for fixing said ratchet wheel with respect to the hand wheel when desired, and means whereby said ratchet wheel can be locked positively in stationary position to permit a slow hand feed.

6. In a grinding machine, the combination with a wheel slide, of a feed screw for operating it, a hand wheel on the feed screw adapted to be positively connected thereto and disconnected therefrom, a ratchet device connected with said feed screw comprising an oscillatable member having a pawl thereon, a ratchet wheel having teeth in the edge in position to be engaged and operated by said pawl, a plate fixed with respect to said hand wheel, means for locking said ratchet wheel to the plate where desired, means whereby said ratchet wheel can be locked positively in stationary position, and means whereby the rotation of the hand wheel can be transmitted to the shaft at a comparatively low speed.

10. 7. In a grinding machine, the combination with a wheel slide, of a feed screw for operating it, a hand wheel on the feed screw adapted to be positively connected thereto and disconnected therefrom, a ratchet device connected with said feed screw, a ratchet wheel in position to be engaged and operated by said ratchet device, a plate fixed with respect to said hand wheel having edge notches, a lock pivoted on the ratchet wheel and adapted to engage in said notches for locking said ratchet wheel to the plate, and means for engaging said lock when removed from the plate whereby said ratchet wheel can be locked positively in stationary position.

8. In a grinding machine, the combination of a feed screw, a grinding wheel slide connected therewith and operated thereby, a ratchet wheel rotatably mounted on the feed screw and having ratchet teeth throughout part of its circumference, a pivoted lock on the ratchet wheel at its portion not provided with teeth, a hand wheel having notches adapted to be engaged by the lock to lock it to the ratchet wheel,

means for turning the ratchet wheel by a slow motion, and means connected with the hand wheel for transmitting motion to the feed screw from the hand wheel or ratchet wheel.

70

9. In a grinding machine, the combination with a wheel slide, of a feed screw for operating it, a ratchet wheel loosely mounted on the feed screw, means for transmitting the rotation of the ratchet wheel to the feed screw at a low speed, and means for operating the ratchet wheel comprising a member oscillatably mounted on said feed screw and having two pawls pivoted thereon in alinement with each other, the distance between the operative edges of said pawls being greater than the space between two of the teeth of the ratchet wheel and less than the sum of the spaces between said two teeth and that covered by the next tooth.

10. In a grinding machine, the combination of a grinding wheel slide, a feed screw connected therewith for feeding said slide back and forward, a ratchet wheel rotatably mounted on said screw, a hand wheel rotatably mounted on said screw, a gear fixed to the screw, a second gear having a different number of teeth but of substantially the same diameter as the first named gear and fixed with respect to said ratchet wheel, a movable pinion supported by the hand wheel adapted to mesh with both of said gears in one position thereof, said hand wheel having a plate thereon provided with notches, means on said ratchet wheel for locking it to the notched plate when desired, a ratchet device for operating the ratchet wheel, a reciprocable work table, a reversing lever therefor, and means connected with said reversing lever for operating said ratchet device.

11. In a grinding machine, the combination of a grinding wheel slide, a feed screw connected therewith for feeding said slide back and forward, a ratchet wheel rotatably mounted on said screw, a gear fixed to the screw, a second gear having a different number of teeth but of substantially the same diameter as the first named gear and fixed with respect to said ratchet wheel, a slideable pinion adapted to mesh with both of said gears in one position thereof and with the first named gear in the other position, a hand wheel rotatably mounted on said screw, means on said ratchet wheel for locking it to the hand wheel when desired, and a ratchet device for operating the ratchet wheel by power.

12. In a grinding machine, the combination of a feed screw, a hand wheel, a gear fixed to the feed screw, a concentric gear with a different number of teeth rotatable with respect to the feed screw, a pinion adapted to mesh with both of said gears,

125

130

means for holding the second gear stationary, whereby the rotation of the hand wheel will rotate the feed screw slowly and means for fixing the second gear to the hand wheel, whereby the hand wheel will rotate the feed screw at its own speed.

13. In a grinding machine the combination with a grinding wheel slide and a feed screw connected therewith for feeding it, of a hand wheel rotatable on the feed screw, a gear fixed to the feed screw, a concentric gear with a different number of teeth rotatable on the feed screw, a pinion adapted to mesh with both gears, and means for holding the second gear stationary to permit the rotation of the hand wheel to operate the feed screw through the two gears and pinion.

14. In a grinding machine, the combination with a grinding wheel slide and a feed screw for operating it, of a hand wheel rotatable with respect to the feed screw, a gear fixed with respect to the feed screw, a concentric gear having a different number of teeth rotatable with respect to the feed screw, a pinion meshing with both gears, and means for fixing the second gear to the hand wheel whereby the hand wheel will rotate the feed screw at its own speed.

15. In a grinding machine, the combination with a grinding wheel slide and a feed screw for operating it, of a hand wheel rotatable with respect to the feed screw, a gear fixed with respect to the feed screw, a concentric gear having a different number of teeth rotatable with respect to the feed screw, a pinion meshing with both gears, and means for fixing the second gear to the

hand wheel whereby the hand wheel will rotate the feed screw at its own speed, said 40 pinion being carried by the hand wheel and being movable to a position in which it does not engage the second gear for the purpose of throwing the feed screw out of connection with the hand wheel.

16. In a grinding machine, the combination with a grinding wheel slide and a feed screw connected therewith for feeding it, of a hand wheel rotatable on the feed screw, a gear fixed to the feed screw, a concentric 50 gear with a different number of teeth rotatable on the feed screw, a pinion adapted to mesh with both gears, means for holding the second gear stationary to permit the rotation of the hand wheel to feed the screw 55 through the two gears and pinion, and means for rotating said second gear slowly by power.

17. In a grinding machine, the combination with a grinding wheel slide and a feed screw for operating it, of a hand wheel rotatable with respect to the feed screw, a gear fixed with respect to the feed screw, a concentric gear having a different number of teeth rotatable with respect to the feed 60 screw, a pinion meshing with both gears, and means for fixing the second gear to the hand wheel whereby the hand wheel will rotate the feed screw at its own speed.

In testimony whereof I have hereunto set 70 my hand, in the presence of two subscribing witnesses.

CHARLES H. NORTON.
